UNITED STATES PATENT OFFICE.

ALLEN L. THOMPSON AND WALTER H. HOVENDEN, OF SALT LAKE CITY, UTAH; SAID THOMPSON ASSIGNOR TO JAMES E. HOUTS AND ARTHUR GARDNER, OF SALT LAKE CITY, UTAH.

RAIL-JOINT.

SPECIFICATION forming part of Letters Patent No. 764,397, dated July 5, 1904.

Application filed July 9, 1903. Serial No. 164,871. (No model.)

To all whom it may concern:

Be it known that we, ALLEN L. THOMPSON and WALTER H. HOVENDEN, citizens of the United States, residing at Salt Lake City, in the county of Salt Lake and State of Utah, have invented new and useful Improvements 5 in Rail-Joints, of which the following is a specification.

This invention relates to rail-joints, and has 10 for its object to provide a simple, economical, and reliable rail-joint composed of three main pieces so arranged with respect to each other and to the rail as to firmly embrace the meeting ends of the rails and form a firm support 15 at the rail-joint, thus preventing a depression of the rails at the point where they meet and also the spreading of the rails at such point.

The joint hereinafter described overcomes the usual pounding of the wheels and effects 20 a material saving in the ties and the expense incident thereto.

With the above and other objects in view the invention consists in the novel construction, combination, and arrangement of parts, 25 as hereinafter fully described, illustrated, and claimed.

In the accompanying drawings, Figure 1 is a perspective view of a rail-joint constructed 30 in accordance with the present invention. Fig. 2 is a side elevation of the same. Fig. 3 is a cross-section through the rail-joint, taken in line with one of the bolts.

Like reference-numerals designate corresponding parts in all figures of the drawings. 35 The rail-joint contemplated in this invention comprises, essentially, three main parts—namely, a pair of fish-plates 1 and 2 and a base-plate or yoke 3. The base-plate 3 is made perfectly flat, and the base 4 of the rail is 40 adapted to rest squarely thereon, as shown in Fig. 3. In carrying out the present invention the base-plate 3 is provided at suitable points in line with the opposite edges of the base 4 of the rail with a plurality of apertures or 45 slots 5, four of such slots being shown at each side of the rail-joint, although said number may be increased or diminished, as may be found expedient. Each of the fish-plates 1

and 2 comprises an upright web portion 6, which is adapted to be bolted flatwise against 50 the adjacent side of the web 7 of the rail, while the upper edge of the part 6 is adapted to underlie and bear firmly against the lower side of the head 8 of the rail. The lower portion of the fish-plate is bent outward to form a 55 flange 9, which fits against the upper side of the base-flange of the rail, and the outer edge of said portion 9 of the fish-plate is provided with a series of projecting lips or extensions 10, which are inserted through the slots 5 and 60 which after passing through said slots are bent so as to project outward, thereby forming feet which underlie the edge portions of the base-plate 3, as clearly shown in the drawings. The bent feet or extensions 10 of the fish-plates are 65 inserted through the slots 5 of the base-plate, and the securing-bolts 11 are then passed through the meeting ends of the rails and fish-plates and turned up tightly, so as to force the upright portions 6 of the fish-plates against 70 the web of the rail and between the head and base thereof. The rail ends are thus firmly held between the fish-plates at opposite sides and the base-plate lying beneath the same. The rail-joint as a whole is preferably made 75 of sufficient length to straddle and rest directly upon three adjacent ties, as shown in Figs. 1 and 2, so that the projecting feet of the fish-plates will come between the ties, while the meeting-point of the rail-sections 80 will come directly over the middle one of said three ties. In this way the meeting ends of the rails are thoroughly supported and incapable of any relative vertical movement, thereby avoiding the usual pounding of the 85 wheels at the rail-joints. The base-plate 3 is provided at suitable points with holes to receive spikes 13, which are driven into the ties and which anchor all of the parts of the joint thereto. It will be observed that the said projecting lips or extensions 10 of the fish-plates are of a width substantially equal to the length 90 of the slots 5 in the base-plates and that they are bent downwardly and outwardly to engage the adjacent edge portions of the rail-bases, 95 as well as both of the longitudinal edges of said

slots, thus securing a firm clamping together of the entire structure with little or no liability to slipping of the fish-plates and rail-bases relatively to each other.

5 Having thus described the invention, what is claimed as new is—

A rail-joint comprising a base-plate located beneath the bases of contiguous rail-sections and formed with slots which extend vertically therethrough at a distance inwardly from the opposite side edges, the slots being longitudinally alined, and fish-plates secured against portions of the opposite sides of the webs of the rail-sections and the bases of the latter,

said fish-plates having lips projecting from the lower edges thereof at regular intervals and inserted downwardly through and bearing against the under side of the plate between the side edges of the latter and the outer walls of the slots thereof, the lips being bent at the points where they pass through the slots.

In testimony whereof we affix our signatures in presence of two witnesses.

ALLEN L. THOMPSON.
WALTER H. HOVENDEN.
